UNITED STATES PATENT OFFICE

2,440,363

BLOWER

Theodore S. Briskin, Chicago, Ill., assignor to Excel Auto Radiator Company, Chicago, Ill., a corporation of Delaware

Application February 5, 1945, Serial No. 576,234

2 Claims. (Cl. 230—119)

1

This invention relates to improvements in heaters, and in particular to heaters adapted for automobile use.

Automobile heaters and the like, include a heat exchange device, together with means for blowing a stream of air across the surface thereof. In the preferred embodiment of the invention herein shown and disclosed, the heat is supplied by hot water from the cooling system of an automobile. However, it will be evident that the principles of this invention are applicable to heaters other than automobile heaters.

It is an object of this invention to provide a heater in which there is a substantially uniform air flow across the heat exchange device. In most automobile heaters, the fan is disposed adjacent to and behind the heat exchange device or radiator core. The usual axial delivery fan is much more efficient at the periphery, than at points closer to the center, and in the vicinity of the center, air actually flows in the reverse direction. Therefore it will be evident that in the usual type of construction, the peripheral portions of the heat exchange device are called upon to heat a considerably greater volume of air in a given time, than the central portions. Thus the maximum amount of heat is not derived from a core construction of given size. Furthermore, the core sections are generally of rectangular cross section, so that the corners thereof generally lie outside of the path of the air stream which is of circular cross section.

This invention contemplates a construction wherein the heat exchange device and the fan are spaced from each other by a sufficient distance so that there is a substantially uniform air flow through the heat exchange device. Thus greater efficiency is achieved.

More specifically, a housing is provided with a spaced inlet and outlet, and air propelling means are disposed at the outlet which serve to decrease the pressure within the housing. The heat exchange device is disposed at the inlet, and as air rushes in the inlet with an equalized velocity at all portions thereof, it necessarily passes through the heat exchange device and all portions of the air stream are heated to a substantially equal extent.

The location of an automobile heater under a dashboard makes a side inlet preferable to a rear inlet, the outlet being at the front of the heater, this being the portion of the heater that faces the occupant of the automobile. With a side intake the heater can be placed immediately adjacent the partition between the motor com-

2

partments and the passenger compartment of the automobile. Furthermore, if the intake and the outlet are aligned at the front and rear walls of the housing, the parts disposed between the two tend to destroy the uniformity of air flow through the inlet. These obstructing parts include not only the fan motor, but also the blower, which is often provided when a defrosting attachment is built into the heater.

10 It is a further object of my invention to provide a heater construction in which the arrangement of the inlet and outlet is such that the working parts of the air propelling mechanism do not tend to destroy the uniformity of the air flow through the inlet.

A still further object of this invention is to provide in a heater in which the inlet and outlet are not aligned with each other, improved means for insuring uniformity of the air stream passing through the outlet. In other words, it has been found that when the inlet is provided in a side wall, that that portion of the air stream passing through the outlet which has the greatest velocity, is that portion which is most remote from the inlet. This unsymmetrical distribution of the high velocity area of the outlet provides means for correcting this objectionable condition.

Other objects, features and advantages will become apparent as the description proceeds.

With reference now to the figures, in which like reference numerals designate like parts—

Fig. 1 is a front view of an automobile heater embodying a preferred form of this invention;

35 Fig. 2 is a top view thereof;

Fig. 3 is a left end view thereof;

Fig. 4 is a right end view thereof;

Fig. 5 is a section taken along line 5—5 of Fig. 2;

40 Fig. 6 is a section taken along line 6—6 of Fig. 1;

Fig. 7 is an enlarged detail section taken along line 7—7 of Fig. 1;

Fig. 8 is a detailed section taken along line

45 8—8 of Fig. 6;

Fig. 9 is a top view of a modified form of the invention, similar to Fig. 2, but in which certain portions of the housing are broken away to show the built-up shield or correcting device disposed

50 at the outlet;

Fig. 10 is a rear view of the shield; and

Fig. 11 is a detailed view of the shield, shown partly in section.

The housing of the heater is designated by the 55 reference numerals 15, and it is provided with

openings, designated as the inlet 22 and the main outlet 20. The inlet is at one side, as shown in Figs. 2 and 4, and the outlet is in the front wall of the housing. An angular frame 16 is suitably mounted at the main outlet 20, as shown in Figs. 1 and 6, and it is provided with a plurality of shutters 17. These shutters have knobs 18 so that they can be opened or closed to regulate the size of the air stream, and also to deflect the air stream downwardly. A knob 19 is provided on the annular frame by means of which it may be rotated with respect to the housing in order to change the direction of the deflection of the air stream, it being understood that the shutters rotate with the frame.

A defrosting outlet duct 21 is provided at the left end of the housing 15. The inlet 22, as shown in Fig. 5, is provided with a suitable screen 23 to keep foreign matter out of the housing. Louvers 24 are provided in the front wall of housing 15, at one side of the outlet 20, these louvers forming an additional intake, as will be hereinafter described.

A suitable mounting plate 25 is provided at the rear of the heater, whereby it may be mounted in an automobile. Also extending from the rear of the housing are inlet and outlet pipes 26 and 27, respectively. These connect with a radiator core 28 which is disposed in the housing adjacent the inlet 22. The radiator core includes the usual headers 42 and 43 which form a connection between the inlet and outlet pipes and the core proper.

Secured to suitable lugs 30 which form a part of the housing 15, is a vertical support 31. A fan motor 32, as clearly shown in Fig. 6, is carried by the vertical support. The motor shaft 33 carries at its front end an axial delivery fan 34, and at its rear end a radial delivery fan or blower 35. The central portion of the blower 35 comprises an inlet 36, and the arrangement of the blades of the blower 35 is shown in Figs. 6 and 8. Associated with the blower 36, and mounted on the vertical support 31, is a collecting shell 37 which is in communication with the outlet duct 21. Thus it will be seen that when the motor is energized, both the fan 34 and the blower 35 will be rotated, and one stream of air will be blown through the outlet 20 by the fan 34, and another stream will be blown through the defrosting outlet duct 21 by blower 35. The reduced pressure within the housing 15, occasioned by the operation of these elements will cause air to be drawn into the inlet 22 and past the radiator core 28.

Disposed at the main outlet 20, and surrounding the fan 34, is a short duct or shield 38. The shield 38 is provided with a flange 40 by means of which it may be secured with respect to the housing, as shown in Fig. 6. A protecting screen 41 may be disposed across the outlet 20 in the usual manner.

The construction of the louvers 24 is shown in detail in Fig. 7. These are merely stampings in the housing 15, and they form additional inlets 44 which permit an additional supply of air to be drawn through the side portions of the core 28, thus utilizing to a greater extent, the full cross sectional area of the core.

In operation, the joint action of the fan 34 and the blower 35 reduces the pressure within the housing 15. This causes air to pass into the housing through the inlet 22. The fan and the blower are spaced a sufficient distance from the inlet, that the reduced pressure at the inlet is substantially uniform at all portions. This 75

means that an air stream of uniform velocity will pass through the core, thereby utilizing all portions of the core and making for greater efficiency. A portion of the transversely moving air stream will be drawn into the collecting shell 37, by means of the blower 35, this being the portion which passes through the rear portion of the core 28. The remainder of that portion of the transversely flowing air stream will pass around the shell and will flow forwardly. It will be noted that a portion of the housing, designated by the reference numeral 45, is diagonally disposed, which may be of assistance in changing the direction of the air stream.

15 The fan motor 32, being of circular cross section, does not constitute such an impediment to the flow of the transverse air stream as would cut down the efficiency of the device, this being for the reason that the circular section is parallel to the path of the horizontally flowing air stream. It has been found that the velocity of the transversely flowing air stream at the inlet 22 is substantially uniform for all portions of the area of the inlet.

20 25 In Figs. 9, 10 and 11 is shown a modified form of my invention, in which the shield 38 shown in Figs. 1 to 8, inclusive, is of a different form. The other parts of the modification are substantially identical with the device shown in Figs. 1 to 8, and are therefore provided with the same reference numeral, and will not be further described herein.

30 35 That side of the shield 38 which is close to the core 28 is built up, as indicated by the reference numeral 39. This built-up portion forms a partial barrier to cause deflection of the air passing through the inlet 22, so that there will be a more even distribution of the air stream which passes through the outlet 20.

40 45 50 55 60 It has been found that without the built-up portion, that portion of the air stream passing through the outlet which has the greatest velocity is the peripheral portion of the air stream which is on the remote side of the center of the shaft. It has further been found, that in that portion of the outlet which is toward the radiator core, the air actually flows in the reverse direction. Furthermore, the reverse direction air flow is extended from a small area around the center of the outlet, to a larger area which extends downwardly and in said remote direction. However, when the shield is built up as indicated by the reference numeral 39, the characteristics of the air stream passing through the outlet 20 are substantially symmetrical with respect to the axis of the fan. This produces a much more efficient construction, not only from the viewpoint of the delivery of the heated air stream, but also it results in a greater lowering of the pressure within the housing 15, and consequently causes a greater volume of air to be drawn through the core 28.

65 70 75 The operation of the modification is substantially the same as pointed out with respect to Figs. 1 to 8, with the exception that the built-up portion of the shield 39 causes a better pressure distribution across the outlet 20.

The transverse incoming air stream apparently has a certain amount of inertia which would ordinarily cause it to pass all the way across the housing so that the resulting air stream passing through the outlet 20 would be concentrated at a remote portion of the outlet. However, the presence of the built-up portion 39 apparently causes a low pressure area which de-

flects a portion of the transversely moving air stream so that the forwardly moving air stream is substantially symmetrical.

It will be apparent that various modifications and changes may be made in the preferred embodiments of the invention herein shown without departing from the spirit of the invention.

The foregoing description and the drawings are deemed to be illustrative only, and the invention to be limited only by the following claims.

I claim:

1. In a heater in which the parts are arranged so that the inlet air stream moves in a transverse direction with respect to the outlet air stream, and having a fan disposed in the path of said outlet air stream, an interiorly extending duct disposed around said fan, said duct being built up at the windward side so as to form a partial barrier for said transversely flowing air stream.

2. In a heater in which the parts are arranged so that the inlet air stream moves in a transverse direction with respect to the outlet air stream, and having a fan disposed in the path of said outlet air stream, an interiorly extending

duct disposed around said fan, said duct being built up at the windward side so as to form a partial barrier for said transversely flowing air stream, and a motor for said fan having a housing of substantially circular cross section whereby the velocity distribution of the outlet air stream is substantially symmetrical with respect to the axis of said fan.

THEODORE S. BRISKIN.
